UNITED STATES PATENT OFFICE.

PETER VANDEN BERGHE, OF PHILADELPHIA, PENNSYLVANIA, ASSIGNOR
OF TWO-THIRDS TO EDWARD W. RICHARDS AND ALFRED H. MEAR,
BOTH OF SAME PLACE.

TINNER'S SEAMING-TOOL.

SPECIFICATION forming part of Letters Patent No. 319,761, dated June 9, 1885.

Application filed February 10, 1885. (No model.)

To all whom it may concern:

Be it known that I, PETER VANDEN BERGHE, a subject of Belgium, residing in the city and county of Philadelphia, State of Pennsylvania, 5 have invented a new and useful Improvement in Tinmen's Seaming-Tools, which improvement is fully set forth in the following specification and accompanying drawings, in which—

10 Figure 1 represents a top or plan view of a seaming-tool embodying my invention. Fig. 2 represents a front view thereof. Figs. 3 and 4 represent views of opposite ends thereof. Fig. 5 represents a vertical section in line *w w*, Figs. 1 and 3. Fig. 6 represents a vertical section in line *x x*, Fig. 1. Fig. 7 represents a vertical section in line *y y*, Fig. 1. Fig. 8 represents a vertical section in line *z z*, Fig. 1. Fig. 9 represents a vertical section similar to 20 that of Fig. 7, the parts being, however, in different positions. Figs. 10, 11, 12, and 13 represent the different steps in the formation of a seam by employment of the tool embodying my invention.

15 Similar letters of reference indicate corresponding parts in the several figures.

25 My invention consists of a tool adapted, first, for bending a piece of metal so that it laps over another piece of metal, and then 30 bending both pieces at the lap so as to form a double seam, as will be hereinafter fully set forth.

35 Referring to the drawings, A represents the bed or frame of the tool, and B represents a rotary bender, which is journaled to the ends of the bed, as at B', and provided with an operating-handle, C.

40 D represents a movable clamp, which has a working-face, E', against which B is brought in contact, the bed A having a working-face, E, the bender B being adapted to work against both faces E E', as shown in the drawings. To 45 said clamp is connected an arm, D', which is provided with a nose, F, the latter entering the groove of a rotary cam, G, which is properly mounted on the bed or frame of the tool and provided with an operating-lever, H.

C' represents set-screws, which are passed

through the bearings B' of the bender B and adapted to tighten against said bender for 50 clamping or locking the same. To the frame or bed is pivoted or hinged, as at J', a stand or block, J, and to said bed is secured a movable block, K, the blocks J K being on opposite sides of the base of said bed for the purpose of adjusting the height of the tool, the block K being raised or lowered by means of inclined ways M, which are secured to a slide, M', operated by a screw, L, and which ride in guides N, secured to the block K. The bearings B' are secured to the main portion of the frame or bed A by means of screws P.

The object of the invention is the formation of the double seam shown in Fig. 13, for which purpose I employ sheets of metal having 65 flanges of different lengths, the first step being the bending of the end of the longer flange laterally over the end of the shorter flange, as in Fig. 10, then bending down said end, as in Fig. 11, bending out the lapped ends, as in 70 Fig. 12, and, finally, bending down said ends against the side of the short flange, whereby the ends of the flanges are inclosed and a double seam is produced, the same being tightly closed and of a superior order.

75 The operation is as follows: Two pieces of metal having flanges of different lengths are placed together, so that the flanges are back to back, and the flanges introduced into the tool between the bed A and clamp D, which 80 are primarily separated. It will be seen that the clamp D occupies only about one-half of the length of the bed; also that for the first operation the stands or blocks J K have been lowered. The handle C is now grasped, and 85 the rotary bender B given a motion forward. The result of this operation is the bending downward of that portion of the longer flange of the two pieces of metal over the face E' of the clamp D, the result whereof is shown in 90 Fig. 10. The tool is now moved along in the direction of the part bent over, a distance nearly equal to the length of the clamp D. The portion bent now occupies a place in front of the face E of the bed A. The operation 95 being repeated, the portion bent, as shown in

Fig. 10, is now compressed by the lug on the left hand of the bender B, (see Figs. 1 and 2,) and pressed down, as shown in Fig. 11. While this is being done a new and adjacent portion of the longer of the two flanges of metal is bent, as shown in Fig. 10. This operation is continued to the end of the seam. (See Figs. 6 and 7.) To clamp and release the two flanges of metal, the handle H is properly operated, turning the grooved cam G, and by means of the nose F, riding in said groove, the arch or arm D', connected to the clamp D, is moved toward or from the bed A, thus making a space between the clamp D and bed A for the ready introduction of the flanges of metal. The main end of the clamp D and inner end of the bender B, being adjacent, are rounded or bulging in opposite directions, so that the metal in passing through the different angles in crimping will not be abruptly bent or broken. Having accomplished this, the block J is swung up, being journaled at J' in the ends B' of the bed, (see Figs. 8 and 9,) and the block K is drawn inward by slackening the screw L and moving the same, and consequently the slide M', so that the lugs M ride in the guides N and draw the block K into the bed A of the tool. It is evident that this lowers the machine the thickness of the blocks J and K. The operation as described for the

first bend is now repeated, the result whereof may be seen in Figs. 12 and 13. To gain additional purchase on the bender, I may add another handle, (shown in dotted lines in Fig. 1,) and I may also pivot both blocks J and K, 35 or make them both to raise and lower by a sliding motion.

Having thus described my invention, what I claim as new, and desire to secure by Letters Patent, is—

40

1. The clamp D, having the face E', in combination with the arm D', provided with the nose F, rotary cam G, said cam having bearings in the bed A, and the bed A, substantially as and for the purpose set forth. 45

2. The bed A, in combination with the bender B, having suitable bearings in said bed and provided with the handle C, die D, arm D', having nose F, rotary cam G, handle H, and blocks J K, substantially as and for the purpose set forth. 50

3. In combination with the bed of a seaming-tool, the slide M', having inclined ways M, the block K, having guides N, and screw L, substantially as and for the purpose set forth. 55

PETER VANDEN BERGHE.
